UNITED STATES PATENT OFFICE

FRED A. POLLMILLER, OF FORT MADISON, IOWA

ADJUSTABLE TEMPLE FOR SPECTACLES

Application filed March 22, 1928. Serial No. 263,889.

My invention relates to spectacles or goggles and particularly to temples therefor, the present invention being an improvement over the structure disclosed in Letters Patent No. 1,591,181, issued to me on July 6, 1926, and having for its principal object to provide means for more readily adjusting the temples for the efficient positioning of the lenses and the comfort of the wearer, and to stabilize the sections of the temples in their adjusted position.

In accomplishing these and other objects of the invention I have provided improved details of structure, the preferred forms of which are illustrated in the accompanying drawings, wherein :

Fig. 1 is a perspective view of a pair of spectacles including temples embodying my invention.

20 Fig. 2 is an enlarged side view of one of the temples, the socket member and loop tip being in longitudinal section and the loop member partially broken away for better illustration.

25 Fig. 3 is a plan view of the temple, the socket being in central transverse section and illustrating a latch in closed position.

Fig. 4 is a cross section on the line 4—4, Fig. 3.

30 Fig. 5 is a detail perspective view of telescoping ends of the socket and loop members, a part of the socket being broken away and the latch being illustrated in open position.

Referring more in detail to the drawings:

35 1 designates a spectacle frame including rims 2 and 3 connected by a bridge 4, and carrying lenses 5 and 6. Hinged to the outside of each of the rim members 2 and 3 are temples 7, each comprising a bar-like socket 8 and a bow or ear loop member 9. Each socket member comprises preferably a substantially cylindrical tube having a reduced bore 10 provided with internal threads 11 for the external threads 12 on a rod 13 and a flexible core wire 14 comprising an element of the loop 9 is fixed to the rod 13. The core wire is resilient and covered throughout its length with a spiral ribbon 15 forming a housing for the core wire and of a diameter to seat snugly and slide within the outer end of the socket,

the inner end of the ribbon abutting against the end of the threaded rod 13, and its outer end abutting against an elongated shell-like button 16 on the wire.

55 The button 16 is interiorly threaded to serve as a nut for a bolt head 17 on the end of the core wire 14 and is crimped at its inner end to produce an inwardly extending flange 18 providing the abutment for the outer end of the spiral ribbon, which is slidable 60 over the core wire and tends to extend therewith. The flange 18 also may engage the bolt head and thus serve to retain the button on the loop.

65 The core wire is initially curved to a curvature for substantially fitting of the curved end of the loop to a position back of the ear of the wearer. To vary the arc of the loop 9, the button is turned on the bolt head 17 to permit the ribbon to expand or cause the ribbon to contract. When the ribbon is contracted the inner circumference is compressed to a greater degree than the outer circumference, tending to reduce the radius of the arc; and when the ribbon is permitted to 70 expand, the radius is increased, so that a loop end of larger curve is provided, the nature of the curved end being thus accommodated to the shape and size of the ear of the wearer.

75 80 The length of the temple is readily adjustable, through the structure described, by moving the loop into or out of the socket, that is to say, by screwing the rod 13 along the reduced bore portion of the socket. To retain the loop and socket member in fixed set position, I provide a locking latch 19 comprising a flat tongue extending in a plane containing the axis of the rod, and movable through a longitudinal slot 20 in the wall of the socket into one of a pair of longitudinal slots 21 and 22 (Fig. 4) formed in the rod 13 to lock the rod in the socket against rotation. The latch retreats into the slots, and when in latching position its outer face is flush with the periphery of the socket. The latch 19 is hinged by a pin 23 between a pair of slightly projecting ears 24 formed integrally with the socket on each side of the slot 20 thereof.

95 100 The latch is preferably provided with a

tapered end 25 adapted for engagement by an operating member such as a finger nail or pointed implement that may be projected into the slot, for swinging the latch out of locking position.

A depression 26 in the socket is further preferably provided for more convenient access to the tapered end of the latch.

Attention is called to the provision of two slots in each rod 13 at right angles to the plane of the curved portion so as to eliminate the necessity of providing separate right and left temple portions, one slot being used when the loop is placed in the right socket 15 and the other when inserted in the left socket, so that the curved ear portion will always be projecting in the right direction.

In adjusting the temples constructed as described, a finger nail of the operator is inserted under the tongue-like latch to swing the tongue back out of engagement with the threaded rod so that the loop member may be turned in the socket to effect the desired adjustment as to length. When the desired adjustment has been made the latch is swung back into locking position with the threaded rod to again lock the rod from turning in the socket.

Adjustment of the curvature of the bow is effected by adjusting the cylindrical nut as above described.

It is apparent, therefore, that standard temples are provided which may be adjusted as to length and curvature of the loop to fit any patient; and the adjustment may be readily altered by the patient himself at his pleasure, both with reference to the length of the temple members and the curvature of the loops, for comfort and efficiency. Glasses 40 or goggles so adjusted will, therefore, not only fit the wearer more comfortably, and be supported more firmly, but will be stably supported during wear in the position for which they are designed to improve vision.

45 What I claim and desire to secure by Letters Patent is:

1. In a device of the character described, a temple member, a loop member adjustably engaged with the temple member and including a resilient wire, a bolt head on the outer end of the wire, a button screw-threadedly movable on the bolt head and including a portion movable over the wire adjacent said head, and a longitudinally extensible member mounted on said wire and tending to extend, said extensible member conferring curved character on the wire proportionate to its extension, and being engageable with said button portion for retention in a desired wire-curving position.

2. In combination with a spectacle frame, temples connected with the frame, each comprising a socket having a reduced screw-threaded inner end, and having a longitudinal slot extending through the socket to the

inside thereof, a temple member having a screw portion threaded into the socket, the screw portion having longitudinal grooves registerable with said slot upon rotation of said temple member, and a latch pivotally mounted in the slot for engaging in one of said longitudinal grooves to retain the parts in adjusted position.

3. An adjustable tongue for spectacles including a tubular socket, a spiral member, and means adjustably retaining the spiral member in engagement with the socket including a resilient wire extending through the spiral member and anchored to the socket, means engaging the inner end of the spiral member to anchor the same against movement on said wire toward the socket, a threaded head-like member on said wire having greater diameter than the same, a button threaded on said head elongated to provide a threaded area of substantially greater extent than the head, and means on said button movable over the wire adjacent said head forming an abutment to receive the outer end of the spiral member.

4. A device of the character described, including a pair of tubular bars, each having a threaded bore portion and a longitudinal slot communicating with said portion, latches pivoted to said bars to move to and from said bore portions through said slots, and a member having one end curved to form an ear loop and an opposite cylindrical end portion threaded to rotatively engage in the threaded bore portion of either one of said bars and provided with a plurality of parallel longitudinal grooves spaced circumferentially of said member and having substantially the same width as said slots to selectively receive the latch of the bar in which the member may be mounted.

In testimony whereof I affix my signature.
FRED A. POLLMILLER.
